UNITED STATES PATENT OFFICE

2,427,758

AIRPLANE HEATER HAVING PRESSURE
DIFFERENTIAL FUEL CONTROLLynn A. Williams, Jr., Northfield, Ill., assignor to
Stewart-Warner Corporation, Chicago, Ill., a
corporation of Virginia

Application February 19, 1943, Serial No. 476,429

7 Claims. (Cl. 158—28)

1

My invention relates to heater carbureting systems, and more particularly to the carbureting systems of heaters intended for use in airplanes, or other purposes, in which relatively great changes in altitude are present.

An object of my invention is to provide a heater carbureting system wherein the fuel is supplied to the heater under pressure, so that no additional pressure drop across the heater is required to supply the fuel thereto, as is necessary in the conventional Venturi type of carburetor, and wherein further means is provided to compensate the fuel supply means for changes in altitude to prevent the fuel mixture supplied from becoming excessively rich at high altitudes.

A further object of my invention is to accomplish the foregoing object by means of a simple, light, inexpensive, and durable structure, having a minimum of moving parts, and capable of long life.

Other objects and advantages will become apparent as the description proceeds.

In the drawings:

Fig. 1 is a view showing one embodiment of my invention, and wherein the heater is shown in longitudinal section for clearer illustration;

Fig. 2 is a longitudinal sectional view of the fuel supply means shown in the upper part of Fig. 1; and

Fig. 3 is a view taken on the line 3—3 of Fig. 2.

In Fig. 1, I have illustrated my invention as being used in connection with an internal combustion type of heater, having a combustion chamber 10 supplied with combustible mixture from an induction pipe 12 communicating with the combustion chamber through slots 14. An electrical igniter 16 serves initially to ignite the combustible mixture supplied to the combustion chamber 10, and is ordinarily provided with a thermostatic switch which disconnects it from its source of electrical current when the heater attains normal operating temperature. A re-igniter 18 is provided to insure maintenance of combustion after the igniter 16 has been disconnected from its source of electrical energy.

The hot products of combustion formed in the combustion chamber 10 flow from the right-hand end of this chamber into a tubular heat exchanger 20 of the hollow fin type. The ends of the hollow fins are sealed, as indicated at 22 and 24. A muffler 26 directs the hot products of combustion into the left-hand ends of the hollow fins, and as the hot gases traverse these fins, the heat from the gases is transmitted to the heat exchanger 20. The cooled gases flow from the

2

right-hand ends of the hollow fins into an outlet chamber 28, which communicates with atmosphere through a discharge fitting 30 and any suitable exhaust pipe which may be attached to the threaded end 32 of this fitting.

The muffler 26 has a sheet metal shell 34 provided with openings 36 forming acoustic couplings between the gas passages and the interior of the muffler, which is filled with sound absorbing material 38, such as stainless steel wool or glass wool. The muffler may be provided with a nose 40 forming an empty acoustic chamber 42 connected by openings 44 to the interior of the main part of the muffler.

15 A fuel jet 46 is located in the induction pipe 12 and is supplied with fuel by a pressure fuel supply means indicated generally by the reference character 48, and connected to the jet 46 by a pipe 50. The fuel supply means 48 operates on the difference in pressure between the combustion chamber 10 and the inlet of a ram 52 which is connected to the pressure device 48 by a pipe 54. Pipe 56 connects the fuel supply means 48 with the combustion chamber 10. A pipe 58 connects the fuel supply means with a fuel pump, elevated tank, or other source of fuel under pressure.

20 Referring to Fig. 2, it will be seen that communication between the fuel pipe 58 and a chamber 60 is controlled by a valve 62 which is moved to closed position by a lever 64 pivoted on an adjustable support 66. This support may be shifted by an adjusting screw 68 against which the support is urged by a spring 70. The other 25 end of the lever 64 is pivotally connected to an operating rod 72 attached to a disc 74, closing one end of a bellows 76.

The other end of the bellows 76 is attached to the wall 78 of a casing 80 so that the interior of 30 the bellows 76 constitutes a variable chamber in communication with the ram 52 through the pipe 54. That part of the casing 80 which is external of the bellows 76 and disc 74, constitutes a second variable chamber 82 which communicates through pipe 56 with the combustion chamber 10. The disc 74 is thus subjected to the differences in pressure between the combustion chamber 10 and ram 52, and this difference in pressure controls the position of the valve 62 and 35 also the pressure in the fluid chamber 60, which extends into the interior of a bellows 84 surrounding the valve operating rod 72. The difference in pressure between the ram 52 and combustion chamber 10 acts over substantially the entire 40 area of the disc 74 and the force thus created

acts upon the relatively small cross sectional area of that portion of the fuel chamber 60 which extends into the bellows 84, so that the pressure difference between the ram 52 and combustion chamber is stepped up and acts upon the fuel in the fuel chamber 60 to force this fuel to the jet 46.

The combustion chamber 10 and heat exchanger 20 are surrounded by a cylindrical casing 86 which is connected to an air inlet 88 attached to the usual ram. In the particular form of my invention shown in the drawings, the same ram and inlet provide the combustion air for the induction tube 12. Ventilating air flows between the heat exchanger 20 and casing 86, and picks up heat from the heat exchanger. The heated ventilating air flows from the right-hand end of the casing 86 directly into a cabin or other space to be heated, or into a duct system having outlets at selected locations.

When such a heater is installed on an airplane in flight, the air supply, of course, varies as the airplane changes its altitude. At higher altitudes, the air is rarefied so that the mass flow will be reduced if the velocity of air flow through the heater remains the same; but frequently the airplane maintains higher speeds at higher altitudes, thus altering the velocity of air flow. It will simplify consideration of the present invention to consider the effect of changes of altitude with the mass flow of air maintained at a uniform rate. For example, when an airplane provided with a heater of this type increases its altitude, the pressure drop between the ram 52 and the combustion chamber 10 will increase, if it be assumed that the mass flow of air is kept constant, as by increasing the speed of the airplane enough to compensate for the reduced density of the air at the higher altitude. But this increase in the pressure drop would actuate the bellows 76 in a manner to increase the richness of the mixture supplied to the combustion chamber, unless compensating means were provided, and a feature of my invention lies in the provision of such means.

This altitude compensating means may assume various forms, the particular means shown being that disclosed and claimed in the copending application of William A. Marshall, Jr., Serial No. 480,974, filed March 29, 1943, now Patent No. 2,381,358, issued August 7, 1945. The function of this compensating means is to control the escape of air from the interior of the bellows 76 and thereby reduce the differential pressure on opposite sides of the disc 74.

In Fig. 2, there is clearly illustrated a tube 90 projecting into the interior of the bellows 76 and provided with a longitudinal slot 92. A valve 94 is slideable in the tube 90 and regulates the escape of air from the interior of the bellows 76 by way of slot 92 and tube 90.

The valve 94 has a stem 96 attached to the end 98 of an evacuated bellows 100 supported in a housing 202 by an adjustable screw 104. A spring 106 tends to expand the bellows 100 and move the valve 94 toward open position. The bellows 100 is collapsed by the pressure in the chamber 108 surrounding this bellows. This chamber communicates by way of pipes 110 and 56 with the interior of the combustion chamber 10, so that the pressure in the chamber 108 varies with the pressure in the combustion chamber.

In the operation of my heater carbureting system, the air supplied by the main ram creates a

pressure at the inlet of the ram 52 which is greater than the pressure in the combustion chamber 10. This difference in pressure acts on opposite sides of the disc 74, moving this disc to the left and permitting valve 62 to open. Fuel flows under pressure into the fuel chamber 60 and is supplied to the jet 46 under a pressure determined by the pressure differential on opposite sides of the disc 74. As heretofore explained, the pressure in the fuel chamber 60 is much greater than the pressure difference on opposite sides of the disc 74, but if the pressure in the fuel chamber 60 rises to too great a value, disc 74 is moved to the right and valve 62 is closed or moved toward closed position to reduce the rate of fuel supply to the chamber 60.

With increases in altitude, if the mass flow of air be kept constant the pressure differential between the ram 52 and combustion chamber increases, but the absolute pressure in the combustion chamber 10 decreases. This decrease in pressure is communicated to chamber 108, permitting bellows 100 to expand and move valve 94 to uncover a portion of slot 92. The uncovered portion will vary in length with the altitude attained. Air escaping from the interior of bellows 76 through slot 92 will prevent the pressure differential across disc 74 from increasing with the increase in altitude, and will maintain a uniformly rich mixture supply for the combustion chamber. The air escaping through slot 92 passes into chamber 108 and through pipes 110 and 56 to the combustion chamber.

While I have illustrated and described only one embodiment of my invention, it is to be understood that my invention is not limited to the details shown and described, but may assume numerous other forms, and that my invention is defined in the following claims.

- I claim:
1. In combination with a heater having a combustion chamber and an induction tube leading thereto, a carbureting system comprising a fuel jet located in said induction tube, means forming a fuel chamber connected to said jet, said fuel chamber having an inlet adapted to be connected to a source of fuel under pressure, a valve controlling admission of fuel through said inlet, an expandable bellows operative on expansion to move said valve in opening direction, a casing enclosing said bellows, a pipe connecting the inside of said bellows with said induction tube, and a pipe connecting the space between said bellows and said casing with said combustion chamber.
  2. In combination with an airplane heater having a combustion chamber and an induction tube leading thereto, a carbureting system comprising a first bellows enclosed in a casing, means connecting the interior of said bellows with said induction tube, means connecting the interior of said casing with said combustion chamber whereby said bellows is responsive to differences in pressure between said induction tube and combustion chamber, means forming a fuel chamber including a second bellows engaging said first mentioned bellows, said fuel chamber being adapted for connection to a source of fuel under pressure, a pipe connecting said fuel chamber with said induction tube for discharge thereinto, and a valve controlling admission of fuel to said fuel chamber and connected to said bellows for movement in opening direction in response to expansion and in closing direction in response to contraction of said first bellows, together with a vent valve for the first bellows and means auto-

matically shifting said vent valve in opening direction in response to decreases in atmospheric pressure and in closing direction in response to increases in atmospheric pressure.

3. In combination with a heater having a combustion chamber and an induction tube leading thereto, a carbureting system comprising a fuel jet located in said induction tube, means forming a fuel chamber in communication with said jet, a valve controlling communication between said fuel chamber and a source of fuel under pressure, a relatively small bellows having its interior in communication with said fuel chamber and forming a part thereof, a relatively large bellows having a common wall with said first mentioned bellows, means operatively connecting said valve to said wall whereby said valve opens in response to expansion of and closes in response to contraction of said large bellows, said bellows being arranged to expand and contract in opposition to each other, a casing supporting and enclosing both of said bellows and forming a space surrounding said bellows, means connecting said space with said combustion chamber, a ram located in said induction tube, and means connecting the interior of said larger bellows with said ram.

4. In combination with a heater having a combustion chamber and an induction tube leading thereto, a carbureting system comprising a fuel jet located in said induction tube, means forming a fuel chamber in communication with said jet, a valve controlling communication between said fuel chamber and a source of fuel under pressure, a relatively small bellows having its interior in communication with said fuel chamber and forming a part thereof, a relatively large bellows having a common wall with said first mentioned bellows, means operatively connecting said valve to said wall whereby said valve opens in response to expansion of and closes in response to contraction of said large bellows, said bellows being arranged to expand and contract in opposition to each other, a casing supporting and enclosing both of said bellows and forming a space surrounding said bellows, means connecting said space with said combustion chamber, a ram located in said induction tube, means connecting the interior of said larger bellows with said ram, and an altitude compensator controlling the escape of air from said larger bellows to prevent the difference in pressure between the interior of said larger bellows and said space from increasing with increases in altitude.

5. In combination with a heater having a combustion chamber and an induction tube leading thereto, a carbureting system including means

forming a fuel chamber, a jet in said induction tube, a pipe connecting said jet and fuel chamber, means for connecting said fuel chamber to a source of fuel under pressure, a valve controlling communication between said source and said fuel chamber, a lever for regulating the position of said valve, a support to which said lever is pivoted, a spring urging said support in one direction, a screw for moving said support in opposition to said spring, and means responsive to the pressure differential between said induction tube and said combustion chamber for shifting said lever in valve opening direction with increases in said pressure differential and in valve closing direction with decreases in said pressure differential.

10 6. In the combination defined in claim 1, an air vent for said bellows, a second casing into which said vent discharges, an evacuated bellows in said second casing, a regulating valve for said 20 vent connected to said evacuated bellows for movement in opening direction in response to expansion and in closing direction in response to contraction of said evacuated bellows, and a conduit connecting said second casing with the combustion chamber.

7. In the combination defined in claim 3, means for regulating the ram pressure applied to said larger bellows, comprising a second casing, a vent connecting said casing with said bellows, a valve controlling said vent, an evacuated bellows mounted in the second casing and operatively connecting to said vent valve whereby said vent valve is moved in opening direction in response to expansion of and in closing direction in response to contraction of said evacuated bellows, and conduit means connecting said second casing with the combustion chamber for actuating the vent valve in response to changes of atmospheric pressure and also conducting to said combustion chamber the air vented from said larger bellows.
